UNITED STATES PATENT OFFICE.

EDWIN S. LEE, OF KANSAS CITY, MISSOURI.

SAFETY HAIR-STRAIGHTENING DEVICE.

1,384,906.

Specification of Letters Patent.

Patented July 19, 1921.

Application filed September 4, 1920. Serial No. 408,187.

To all whom it may concern:

Be it known that I, EDWIN S. LEE, a citizen of the United States, residing at Kansas City, in the county of Jackson and State 5 of Missouri, have invented certain new and useful Improvements in Safety Hair-Straightening Devices, of which the following is a specification.

My invention relates to improvements in 10 hair straighteners, and one object is to provide a device of this character which may be either electrically or otherwise heated.

Another object is to provide a hair straightener in which it is impossible to 15 burn the scalp, and one in which the comb attachment can be adjusted away from the roller when the latter is heated over a flame, thus leaving said comb in a cool condition.

Another object is to provide a device 20 which is pulled through the hair instead of pushed, thus giving a positive motion rather than an unsteady one.

Another object is to provide a multi-grooved roller which has more heating surface than a plain roller, and tends to 25 straighten the hair by causing it to pass through the grooves of the heated roller.

With the above and other objects in view, reference will now be had to the accompanying drawing, in which:

Figure 1 is a plan view of the hair straightening device.

Fig. 2 is a side elevation thereof.

Fig. 3 is a longitudinal section.

Fig. 4 is an end elevation of the device.

In carrying out the invention, I provide a wire handle 2, which is not so likely to become heated as a solid handle. Said handle 2 is provided at its forward end with a cap 40 4, having a forwardly projecting shank 6 which is bifurcated at its forward portion 8.

10 designates a roller which is journaled upon a stationary shaft 12, secured in the bifurcated portion 8 by nuts 13. Said 45 roller 10 is provided with peripheral grooves 14 through which the hair passes while being treated, the grooves 14 providing greater heating surface and also tending to straighten the hair more efficiently 50 than a plain roller.

15 designates an arcuate comb, having oppositely disposed teeth 16, which extend below the roller 10, so that the latter cannot come into contact with the scalp and burn 55 the same. The comb teeth 16 are curved in such manner as to pick up the curly hair

and divide it and then pass it through the grooves 14 of the roller 10. In order that the comb 15 may not become hot, while the roller 10 is being heated over a flame the former is fixed to an arm 18, which may be swung away from the roller 10, said arm 18 having a downturned, bifurcated end 19 which is pivotally mounted upon the shank 6 by means of a pin 20.

When being used, the comb 15 is held in lowered position by means of a turnbutton 22 swiveled in the shank 6, said turnbutton passing through a corresponding opening 23 in the arm 18 which supports the comb.

In order that the roller 12 may be electrically heated it is provided with an interior heating coil 26 surrounding an insulating member 27, through which the shaft 12 extends. The terminals of the heating coil 26 are connected to insulated wires 20 and 32, which extend through the shaft 12 and the handle 2 and connect with a coupling 34 adapted to be connected to any suitable source of current. The coupling 34 is fixed 80 to a cap 36 secured to the rear end of the handle 2.

The operation briefly stated is as follows: When it is desired to straighten the hair, the device is electrically heated if current is 85 available, otherwise it may be heated over a flame, the comb being swung back so that it will not become heated with the roller 10. The comb 15 is then returned to operative position and secured by the turnbutton 22. 90 The device is then placed upon the user's head and pulled backwardly and as it travels along the comb teeth pick up the hair, dividing it into small strands which are directed between the grooves 14 of the 95 heated roller 10, which leaves the hair in a straight condition.

Having thus described my invention, what I claim and desire to secure by Letters Patent, is:

1. A device of the character described consisting of a roller, a shaft upon which said roller is journaled a handle associated with said roller and the shaft, and a comb associated with said handle and partly surrounding the periphery of the roller.

2. A device of the character described consisting of a roller having a multiple of peripheral grooves, a handle associated with said roller, and a comb associated with said handle and partly surrounding the periphery of the roller; the ends of the comb teeth

being directed toward the handle to lift the hair into the grooves of the roller as the device is drawn over the head.

3. A device of the character described 5 consisting of a roller adapted to be heated, a handle associated with said roller, a comb which is curved to extend partly around the roller, and a member movably connected to the handle and carrying the comb to remove 10 the same from the immediate vicinity of the roller while the same is being heated.

4. A device of the character described 15 consisting of a roller adapted to be heated, a handle associated with said roller, a comb which is curved to extend partly around the roller, a member movably connected to the handle and carrying the comb to remove the same from the immediate vicinity of the

roller while the same is being heated, and means for fastening said member from moving independently of the handle when the comb is in position around the roller. 20

5. A device of the character described 25 consisting of a hollow roller, a shaft upon which said roller is journaled, a handle associated with said roller and the shaft, means within the roller to heat the same, and a comb associated with said handle and partly surrounding the periphery of the roller.

In testimony whereof I affix my signature, 30
in the presence of two witnesses.

EDWIN S. LEE.
